UNITED STATES PATENT OFFICE.

ALEXANDER F. SMITH, OF READING, PENNSYLVANIA.

VENTILATING-WINDOW.

No. 923,450.

Specification of Letters Patent.

Patented June 1, 1909.

Application filed January 28, 1909. Serial No. 474,844.

To all whom it may concern:

Be it known that I, ALEXANDER F. SMITH, a citizen of the United States, and a resident of the city of Reading, in the county of Berks and State of Pennsylvania, have invented 5 certain new and useful Improvements in Ventilating-Windows, of which the following is a specification.

The object of my invention is to provide 10 for securing proper ventilation of rooms through the frames of windows of ordinary general construction and independently of the sash movement.

Windows of the vertically-movable-sash 15 type referred to, which are commonly known as double-hung windows, have frames which are formed with weight boxes rearward of the sash runs and with pulley stiles forming walls common to both. Effort has heretofore 20 been made to utilize this box space as a means of ventilating communication between the outer air and the inclosed room. My invention provides for thus utilizing it in such a manner as to properly locate and direct 25 the flowing current of air to secure the most satisfactory results, while at the same time avoiding difficult or unsightly structural changes or additions and permitting convenient regulation of the ventilating flow.

30 The invention is fully described in connection with the accompanying drawing and is specifically pointed out in the claims.

Figure 1 is an inside elevation of a window 35 embodying my improvements, partly in section on the line 1—1 of Fig. 2. Fig. 2 is a section on the line 2—2 of Fig. 1. Fig. 3 is a section on the line 3—3 of Fig. 1.

The general construction of the window indicated in the drawings is well known, and 40 only brief reference is necessary to the ordinary features thereof in connection with which my improvements are employed. The lower sash 2 which is guided in the inner sash runs 3 on opposite sides of the window frame, and the upper sash 4 which is in like manner guided in the parallel outer sash runs 5, are each hung as usual upon pulley cords or chains provided with counterbalance weights 6 which are vertically movable 45 in weight boxes 7 formed in the sides of the window at the rear of the sash runs 3 and 5; each box 7 being divided as shown into communicating weight compartments by a parting strip 8, and the sash runs 3 and 5 being 50 separated as usual by parting beads 9, and

55 bounded by an outer casing or bead 10 and an inner casing or bead 11, while the pulley-stiles 12 partition the sash runs from the weight boxes or compartments at the rear thereof.

In providing for ventilating communication between the outside air and an inclosed room, and particularly in providing for securing an inflowing current of outside air, it is important that the exterior ventilating 60 aperture be so located or protected as to prevent a too free admission of blasts of air by causing the same to be deflected; and also that the interior aperture be arranged to so direct the inflowing air as to prevent or 65 minimize objectionable drafts.

In utilizing the weight boxes formed in the window frames as a means of communication between the outside air and the room, my main object therefore is to provide for 70 a lateral inflow of air to the box from the outside,—that is in a direction parallel with the plane of an adjacent sash which may thus serve to deflect the current,—, and for a like discharge from the box at the inner side of 75 the sash so as to retain the air close to the window until its temperature has been 80 raised.

Further objects are to provide for admitting the outside air to the lower portion of the 85 weight boxes and for discharging it into the room from the upper portion thereof, and to accomplish these results in a simple manner without change in the general window construction and operation.

In the general construction shown it will be seen that when the sashes are in closed position with their meeting rails 2^a and 4^a in juxtaposition, the lower portions of the inner sash runs 3 are loosely occupied by the inner sash 2 while the upper portions thereof are open to the room; and that the upper portions of the outer sash runs 5 are in like manner occupied by the outer sash 4 while the lower portions thereof are open to the outside 90 air. I have found that these conditions permit the attainment of the objects of my invention as above stated in a very simple and satisfactory manner, by merely changing the pulley-stiles 12 from closed walls or partitions 95 between the weight boxes or compartments and the sash runs, as heretofore, to apertured walls or partitions arranged to throw said weight boxes into communication with the outside air at a portion outside of the 100 105 110

lower sash and with the room at a portion inside of the upper sash; and to provide suitable means for regulating the communication by opening and closing said apertures. 5 These apertures or openings in the pulley-stile partitions are shown at 15 in the upper portion of the inner sash-run 3, and at 16 in the lower portion of the outer sash-run 5, and are provided with suitable register devices 10 which may be conveniently operated and which are so arranged as not to interfere with the usual free movement of the sashes.

When the registers at 15 and 16 are opened, the outside air is only admitted to the lower 15 portion of the weight box, at 16, in a lateral direction as indicated by the arrow; the inlet being also protected from direct blasts by the projecting outer casing or bead 10. The air thus admitted to the weight boxes passes up- 20 ward in the latter, and is discharged into the room in reverse direction from that in which it is admitted to the box and in the plane of the lower sash so that its effect as a draft is not felt at any distance from the window.

25 The invention may obviously be readily applied to old windows as well as new, and involves but little expense in excess of the ordinary and no objectionable change in the appearance of the window.

What I claim is:—

1. In a double-hung window, a frame having a side member formed with communicating weight-boxes and inner and outer sash runs, each of said boxes and sash runs having a common pulley-stile wall provided for a portion of its height with ventilating openings to said boxes whereby air is admitted to the latter in the plane of one sash and is discharged therefrom in reverse direction in the plane of the other sash. 30

2. In a double-hung window, a frame having a side member formed with communicating weight boxes and inner and outer sash runs, each of said boxes and sash runs having a common pulley-stile wall the inner one of 45 which is provided at its upper portion, and the outer one at its lower portion, with ventilating openings to said boxes whereby outside air is admitted to the lower portion of the latter in the plane of the outer sash and discharged from the upper portion thereof in the plane of the inner sash. 40

In testimony whereof, I affix my signature, in the presence of two witnesses.

ALEX. F. SMITH.
